UNITED STATES PATENT OFFICE.

CLELAND DAVIS, OF THE UNITED STATES NAVY, ASSIGNOR TO ORDNANCE DEVELOPMENT COMPANY OF AMERICA, OF WILMINGTON, DELAWARE, A CORPORATION OF DELAWARE.

CONTOUR-CAP FOR PROJECTILES.

1,135,772.

Specification of Letters Patent. Patented Apr. 13, 1915.

Application filed January 18, 1915. Serial No. 2,932.

To all whom it may concern:

Be it known that I, CLELAND DAVIS, commander, United States Navy, a citizen of the United States, stationed at San Diego, 5 in the county of San Diego and State of California, have invented certain new and useful Improvements in Contour-Caps for Projectiles; and I do hereby declare the following to be a full, clear, and exact description of the invention, such as will enable others skilled in the art to which it 10 appertains to make and use the same.

My present invention relates to improvements in contour caps for projectiles, and 15 it is intended to provide a hood of such a character as to give the form or contour to the nose of the shell that is best adapted to a minimum resistance of the projectile in its flight through the air; thus causing it 20 to have a greater range, a flatter trajectory, a greater danger space, and a greater final velocity.

The advantages of the long pointed shell have long been recognized by ordnance engineers and the principle has been applied 25 to small arms, bullets, and to armor piercing shell, as described in my Patent No. 945,492, granted January 4, 1912, and entitled Contour cap for projectiles; but certain requirements of design have limited its 30 application in non-armor piercing projectiles. These limitations are due to the fact that when the point is drawn out to a comparatively long radius of ogival, the balance 35 of the shell is disturbed with the result that it wobbles in flight, and hence is not accurate. By lengthening the point, too, the weight is increased, which reduces the ballistic efficiency of the gun, there being a definite 40 weight of shell for each caliber of gun which may not be increased without reducing the muzzle velocity or increasing the powder pressure in the bore. By lengthening the point of the shell, also, its capacity 45 for carrying a bursting charge, a most important desideratum in the design of shell, is decreased. All of these considerations have limited the designers of shell in the application 50 of the long pointed principle.

What I propose is to provide a hood of material of low specific gravity, such as soft rubber, which may be vulcanized to, or otherwise connected to the forward portion 55 of the projectile. In order to give sufficient rigidity to this hood during flight, and also

to protect it against injury incidental to the shock of discharge, or against being deformed in the ordinary handling, this hood may be, on all but the small size of projectiles, wrapped with cord, or steel wire, 60 or tape.

My invention will be understood by reference to the accompanying drawings, in which:—

Figure 1 shows a projectile fitted with an improved rubber hood, wound with metal tape; Fig. 2 shows a similar hood with the metal tape omitted; and Fig. 3 shows the hood applied to the nose of an ordinary rifle bullet. Figs. 2 and 3 are shown partly in 70 section and partly in elevation; and in Fig. 1 parts are broken away.

In Figs. 1 and 2, A represents the body of the projectile which is provided with any suitable nose A', preferably of the ordinary 75 ogival form, and onto this the soft rubber cap B is attached in any convenient way, as by vulcanizing the rubber to the nose of the projectile, as indicated at b in Fig. 2. Outside of this rubber cap a winding or wire 80 tape, or cord, such as C, shown in Fig. 1, may be applied if desired. Instead of this reinforcing winding, the rubber cap may have its exterior vulcanized or hardened to a sufficient depth to maintain the requisite 85 rigidity of the shape of said cap.

In the form of device shown in Fig. 3, an ordinary metal bullet D is provided, with a suitable nose D' to which is vulcanized, as at b, the rubber cap B, which cap is of 90 such shape as to give the proper contour to the surface of the projectile opposed to the resistance of the air. The exterior of this rubber cap may be vulcanized to give stiffness to same, if desired. While I prefer to 95 vulcanize the rubber direct to the metal nose of the projectile, it may be attached thereto in any other convenient way.

Having thus described my invention what I claim and desire to secure by Letters 100 Patent of the United States is:—

1. A contour cap for projectiles, comprising a solid yielding rubber cap secured to the nose of the projectile, substantially as 105 described.

2. A contour cap for projectiles, comprising a solid yielding rubber cap vulcanized to the nose of the projectile, substantially as described.

3. A contour cap for projectiles, comprising 110

ing a rubber cap secured to the nose of the projectile, and provided with a reinforcing winding thereon, substantially as described.

4. A contour cap for projectiles, comprising a rubber cap vulcanized to the nose of the projectile, and provided with a reinforcing winding thereon, substantially as described.

5. A contour cap for projectiles, comprising a rubber cap secured to the nose of the projectile, and provided with a metallic winding on the exterior thereof, substantially as described.

10. A contour cap for projectiles, comprising a rubber cap secured to the nose of the projectile, and provided with a metallic winding on the exterior thereof, substantially as described.

6. A contour cap for projectiles, comprising a rubber cap vulcanized to the nose of the projectile, and provided with a metallic winding on the exterior thereof, substantially as described.

15. In testimony whereof, I affix my signature, in presence of two witnesses.

CLELAND DAVIS.
